UNITED STATES PATENT OFFICE

IRVING L. BAMBRICK, OF BOSTON, MASSACHUSETTS

GOLF CLUB GUIDE

Application filed February 13, 1929. Serial No. 339,649.

This invention relates to apparatus for guiding a golf player when swinging a golf club, an object of the invention being to provide apparatus which allows the greatest possible freedom of motion to the user, but at the same time effectively corrects many of the faults commonly committed by players. Among such faults is a tendency on the part of many to permit the club to get too far out 10 during the downward part of a swing and also as the club is raised for the backward part of the swing. This fault usually arises from a failure to keep the hands and arms sufficiently close to the body. Another 15 faulty tendency often observed is "swaying", that is, moving the head and shoulders sideways as the club is raised prior to a stroke. To correct these and other tendencies, the invention may be embodied in apparatus including a curved rail against the under edge 20 of which the shaft of the club may slide from the beginning of a stroke until after the ball has been hit by the head of the club. In connection with the guide rail I may also provide a suitably located neck-rest which is shaped to hinder motion of the head and shoulders in a direction against the travel of the ball, or in the case of right handed players toward the player's right, but permits 25 motion in the direction of travel of the ball as the player's body follows the club during the follow-through portion of the stroke.

It is a further object of the invention to provide apparatus which is relatively simple, and which is readily adjustable for players of different sizes, or having different styles of swing, such as flat and upright swings, as well as straight and "hook" swings. Further advantageous features will 40 be apparent to one skilled in the art from the disclosure of the invention in the description thereof which follows, and from the drawings of which,—

Figure 1 represents in perspective apparatus embodying the invention.

Figure 2 is a side elevation of the same, a portion being broken away.

Figure 3 is an end elevation of the same.

Figure 4 is a side elevation of a stop shown 50 on a larger scale.

Figure 5 is an end elevation of a stop, the operative and inoperative positions thereof both being indicated.

Figure 6 shows in section a support for the neck-piece.

The apparatus comprises essentially a suitable rail 10 which may conveniently be shaped in a spiral curve as indicated in Figure 2, and is so supported in a slanting plane that the under edge is free throughout its entire extent, so that a player when standing below the plane of the curve with the exception of the head and shoulders, may swing a golf club with the shaft thereof in contact with the lower edge of the rail 10. This effectively prevents the common fault of permitting the club to swing away from the body, both while the club is being raised prior to a drive and also during the drive itself. To this end the rail 10 may be supported by a number of 60 brackets 11, 12 and 13 which may be fixed or adjustably secured thereto and which extend therefrom in a direction opposite to the guiding edge of the rail so as to leave the guiding edge entirely free. As shown in Figure 2, the 65 brackets 11, 12 and 13 may be adjustably secured to a plate 14 by bolts and wing nuts 15 or by any other suitable device, so that the shape of the curve of the rail 10 may be altered to suit the requirements of players of 70 different sizes. The brackets 12 and 13 may be adjustably secured as by bolts and wing nuts 16 to the rail 10 to permit such adjustment of the shape of said rail 10, the material of the rail being sufficiently flexible for 75 this purpose. The rail 10 may be curved in such a way as to lie substantially in a single plane, but I do not limit myself to a plane curve, as portions of the rail may be bent if desired out of the general plane of the curve. 80 The bracket 13 may be hinged as at 50, if desired, to permit a slight amount of yielding outwardly by the lower portion of the guide rail 10. This gives the player a feeling of 85 freedom when addressing the ball and does not impair the guiding function of the rail since the outward pressure of the club during that portion of a swing is negligible. 90 As shown in Figure 3 the degree of slant of the plane of the curve may be adjusted as 95 100

desired by a ball and socket joint 17 or by any other equivalent device. This also permits adjustment of the rail on a perpendicular axis for a straight swing or a "hook" swing. 5 As shown, the ball and socket joint 17 is secured to the end of a single horizontally extending arm 18 which may be adjustably attached to any upright standard, wall or equivalent. As shown the arm 18 has a portion 10 19 extending downwardly and entering a suitable base 20 in which it is adjustably secured by any suitable means so that the height of the rail 10, as a whole, may be altered as desired. To facilitate vertical adjustment of 15 the guide, I may attach to the lower end of the upright 19 a steel tape 40, the opposite end being attached to a windlass drum 41. The drum may be operated as by a handle 42, a ratchet 43 and pawl being provided to retain 20 the apparatus at any desired elevation. At the upper end of the rail 10 I secure a neck-piece 21. This may be secured directly to the end of the rail 10 as shown, or may be otherwise supported in a definite position relative 25 to the rail. The neck-piece 21 is provided with a curved end portion 22, the object of which is to hinder "swaying", that is, motion of the head and shoulders away from the direction of travel of the ball, this being a common fault. The neck-piece, however, does not hinder follow-through motion of the head and shoulders in the direction of travel of the ball, this motion being proper after the ball has been hit. The neck-piece 21 may be 30 rigidly secured to the rail 10 or may be permitted to yield a short distance. For this purpose the neck-piece may be secured to a short sleeve 45 which is slotted to receive a pin 46. A spring 47 may be arranged to 35 press the neck-piece downwardly away from the end of the rail 10.

In order to regulate the proper point at which a swing should begin, I may provide a plurality of stops mounted on the rail, these 40 stops being selectively usable to indicate how far the club should be raised for a full swing, a three-quarter swing and a half swing. A stop for the full swing is indicated as 23 and is preferably located at a suitable position 45 near the neck-piece 21. At other points on the rail 10 I may mount additional stops 24 and 25, these being preferably constructed so as to be readily moved from their operative positions to inoperative positions. As shown 50 in Figures 4 and 5, these stops may each comprise a metal strip 26 having a portion normally parallel to the guiding edge of the rail 10 and an outwardly bent lip 27 to guide the club between the strip 26 and the rail 10. A portion of the strip 26 may be bent inwardly 55 toward the rail as at 28 to engage the club and to stop it at the proper point. The strip 26 as shown is attached to or integral with a plate 29 which extends at right angles thereto 60 and acts as a spacing support, this plate being

hinged as at 30 to another hinge member 31 which is secured to the rail 10. By means of the hinge 30 the stop may be swung upwardly out of operative position, leaving the guiding edge of the rail 10 free. This inoperative 70 position is illustrated in dotted lines in Figure 5.

In using the apparatus the player stands as indicated in Figure 1, the height and slant of the rail 10 being so adjusted that the 75 player's head and shoulders project through the general plane of the curve. A ball is placed on the ground at the proper distance in front of the player. After addressing the ball with the club, the player may raise the 80 club in the ordinary manner until the shaft touches one of the stops. Since the natural tendency of a player is to swing the club away from the body, the shaft of the club will ordinarily ride on the guiding edge of the rail 85 10 as the club is raised for the stroke. The club is then swung in the usual manner, the shaft thereof being in contact with the guiding edge of the rail throughout most of the swing and until after the head of the club has 90 struck the ball. The apparatus permits a maximum freedom of motion on the part of the player and a minimum of restraints, but at the same time it effectively prevents many 95 of the faults which are commonly observed in golf players. I have thus provided an extremely simple but effective device which is readily adjustable to the needs of any individual player.

I claim:—

1. A golf club guide comprising a curved rail, means for supporting said rail in a slanting plane so as to leave the edge of said rail which is toward the player free, said supporting means being adjustable to alter the 105 curvature of the rail and the height thereof, and a neck-piece attached to one end of said rail.

2. Apparatus of the class described, comprising a guide rail for a golf club arranged in a slanting plane, and a support for said rail, said support including a plate spaced upwardly from the plane of said rail and a plurality of arms secured at one end to said rail and at the other end to said plate.

3. Apparatus of the class described, comprising a guide rail for a golf club in the form of a curve lying approximately in a slanting plane, and supporting means extending upwardly from said rail whereby the under edge of the rail is free throughout its entire extent for contact with the shaft of a golf club.

4. Apparatus of the class described, comprising a guide rail for a golf club in the form of a curve lying approximately in a slanting plane, means for supporting said rail entirely from above said plane whereby the under edge of said rail is free, and a neck-rest mounted in a definite position relative to said rail.

5. Apparatus of the class described, comprising a guide rail for a golf club in the form of a curve supported in a slanting plane with its under edge free, and a neck-rest secured to one end of said rail.

6. Apparatus of the class described, comprising a guide rail for a golf club in the form of a curve supported in a slanting plane with its under edge free, and a stop mounted 10 on said rail, said stop being movable from and to operative and inoperative positions.

7. Apparatus of the class described, comprising a guide rail against which the shaft of a golf club may slide during a stroke, and 15 a neck-rest attached to said rail, said neck-rest being shaped to permit motion of the player's neck in the direction of travel of the ball and to hinder motion of the neck in the opposite direction.

20 In testimony whereof I have affixed my signature.

IRVING LEO BAMBRICK.
